US00D708747S

(12) **United States Design Patent**
Curran et al.(10) **Patent No.:** US D708,747 S
(45) **Date of Patent:** ** Jul. 8, 2014(54) **SPINAL FUSION IMPLANT**(75) Inventors: **Matthew Curran**, Carlsbad, CA (US);
Caleb Granger, San Diego, CA (US);
W. Dan Bradley, Denton, TX (US);
Ravinder Bains, Orinda, CA (US); **G. Bryan Cornwall**, San Diego, CA (US)(73) Assignee: **NuVasive, Inc.**, San Diego, CA (US)(**) Term: **14 Years**(21) Appl. No.: **29/381,796**(22) Filed: **Dec. 22, 2010****Related U.S. Application Data**

(63) Continuation of application No. 11/526,421, filed on Sep. 25, 2006, now abandoned.

(51) **LOC (10) Cl.** ..... 24-02(52) **U.S. Cl.**USPC ..... **D24/155**(58) **Field of Classification Search**

USPC ..... D24/155, 133, 135; 606/61, 69, 90, 606/86 R, 248, 249; 623/17.15, 17.16, 623/17.12, 16.11, 20.14; 604/500

See application file for complete search history.

Primary Examiner — Ian Simmons*Assistant Examiner* — Charles Hanson(74) *Attorney, Agent, or Firm* — NuVasive, Inc.; Jonathan Spangler; Jennifer Russell**CLAIM**

(57) The ornamental design for a spinal fusion implant, substantially as shown and described.

DESCRIPTION

FIG. 1 is a perspective view of a spinal fusion implant showing our new design;

FIG. 2 is a top view thereof;

FIG. 3 is a bottom view thereof;

FIG. 4 is a side view thereof; and,

FIG. 5 is a front view thereof.
